[57] CLAIM

The ornamental design for a box, substantially as shown and described.

DESCRIPTION

FIG. 1 is a front perspective view of a box showing my new design;

FIG. 2 is a front elevational view;

FIG. 3 is an elevational view looking from the right of FIG. 2;

FIG. 4 is an elevational view looking from the left of FIG. 2;

FIG. 5 is a rear elevational view;

FIG. 6 is a bottom plan view;

FIG. 7 is an enlarged, fragmentary perspective view of one of the hinge areas;

FIG. 8 is a top perspective view with the lid partially opened;

FIG. 9 is a top plan view with the lid closed; and

FIG. 10 is a top plan view with the lid fully opened.

The drawing is shaded to show contrasting color or the like.
